UNITED STATES PATENT OFFICE.

THOMAS PETER EUSTEDE, OF WELLINGTON, NEW ZEALAND.

WINDOW STAY AND FASTENER.

Application filed May 22, 1925, Serial No. 32,209, and in New Zealand June 6, 1924.

This invention relates to casement window stays and fasteners of the type in which a stay is pivoted to a link so as to turn downwardly to a vertical position, such link being pivoted in a bracket fixed to the sash so as to turn in a lateral direction, the stay passing through a bracket fixed to the window frame which it engages at intervals.

According hereto, the stay is pivoted to the link in such a way that the end of the stay will project above the link. A member upon the bracket fixed to the window frame prevents the stay from rising out of engagement with the bracket. When the stay lies parallel to the bracket, this member will engage between the end of the stay and the face of the bracket in such a way that the sash will be drawn inwardly against the frame of the window.

20 The invention will be illustrated in the accompanying drawings, wherein:—

Figure 1, is a side elevation of the stay.

Figure 2, is a plan.

Figure 3, is an end view of the stay and bracket showing the stay in the position of the dotted lines in Figure 1.

Figure 4, is a sectional plan on line A—A

Figure 3.

Figure 5, is a side elevation of a modified 30 form of stay.

Figure 6, is a plan thereof.

Referring to the drawings, but more particularly to Figures 1 to 4, the stay 1 is pivoted to a link 2 by a pin 3 so that the stay may assume a horizontal position. The link 2 is pivoted by a pin 4 to a bracket 5 fixed by screws to the window sash 6 so as to enable the stay to turn in a lateral direction. A bracket 7 is fixed to the window frame 8 and the stay and link pass through an opening 9 in the bracket 7. A lever 10 pivoted upon the bracket 7 by a pin 11 has a projecting tongue 12 and a depending handle 13. The stay 1 is provided with notches 14 at 45 desired intervals upon its bottom edge, these notches engaging with the edge 15 of the opening 9 and when a notch 14 is in position the tongue 12 prevents the stay from rising upwards out of engagement with the bracket. This is illustrated in Figure 5.

It will be noticed by referring to Figures 1 and 2, that the stay projects beyond the pin 3 so as to leave an end 16 which, when the stay is in the horizontal position, lies in the jaws of the link 2, but when the stay is turned to the vertical position this end

16 projects above the link as shown in Figures 1 and 3, thereby enabling the tongue 12 to engage between the end 16 and the face of the bracket.

By referring to Figure 4, it will be seen that the tongue is tapered and so also is the inside face of the end 16, so that when the tongue is forced between the projecting end 16 and the face of the bracket the tongue will draw the link 2 through the brackets 7 and tighten the sash against the frame. The notches 14 are preferably formed at an angle as suggested in Figure 2, so that as the sash swings out radially the notches will be parallel with the edge of the bracket. At the point where the stay is pivoted to the link the stay is cut away as at 17 so as to enable the stay to pass through the opening 9 in the bracket and when one of the notches therein engages the edge 15 of the bracket the tongue will draw the link 2 through the brackets 7 and tighten the sash against the frame. The notches 14 are preferably formed at an angle as suggested in Figure 2, so that as the sash swings out radially the notches will be parallel with the edge of the bracket. At the point where the stay is pivoted to the link the stay is cut away as at 17 so as to enable the stay to pass through the opening 9 in the bracket and when one of the notches therein engages the edge 15 of the bracket the top edge of the stay will remain in alignment with the top edge of the link 2, and for this purpose the distance between the top edge of the notch and the top edge of the stay is equal to the depth of the link.

In a slight modification, two stay bars 19 and 20 (see Figures 5 and 6) are pivoted, one on each side of a link 21 pivoted in the bracket 5 as before, and when the bars are in a vertical position the ends 16 of the bars project above the link in the same manner as in Figures 1 and 3. At the other end of and between these bars 19 and 20 another bar 23 is pivoted upon a pin 24. The end of this bar 23 is shaped in a similar manner to the ends 16 of the other bars and when in its horizontal position rests against a pin 25 so that the bar 23 will only turn in a downward direction. One of the notches 14 would be arranged near to the end of the bars 19 and 20, as shown in Figure 5, so that when the stay is placed in position in the bracket in such notch the bar 23 will assume the position shown and the tongue 12 of the lever

10 will engage between the end 26 and the face of the bracket in the same way as shown in Figure 3 in regard to the first stay.

In this construction, the lever 10 has another tongue 29, as shown in Figure 6, in order to prevent any tendency of the stay at its jointed position rising beyond the horizontal when the bar 23 is being held in the bracket 7.

10 The handle of the stay may be formed by cutting away a portion of the metal of the stay so as to leave a narrow strip 27 which is turned downwardly to form a loop or partial loop, the opening in the bracket 7 being 15 extended upwards at 28 to admit of the handle being passed through such bracket.

What I claim is:-

1. In a window stay and fastener, a bracket fixed to the window sash, a link pivoted to the sash, a stay bar pivoted to said link, a bracket to receive the said stay bar fixed to the window frame, an end of said stay bar projecting beyond its point of pivoting in said link whereby when said stay bar is turned at its point of pivoting in said link said end will project beyond the face of the said link so that a space will be provided between said end and the face of said bracket on the window frame, a member pivoted to the bracket on the window frame, a portion of said member adapted to enter the space between the face of the said bracket on the frame and the said end of the stay bar and adapted to draw the sash inwardly, substantially as described.

2. In the stay as claimed in claim 1, said stay bar bearing against the said bracket thereby acting as a fulcrum at such point, substantially as described.

40 3. In the stay as claimed in claim 1, the inner edge of said projecting end of said stay bar being tapered whereby said tapered portion may draw the link inwards and so

draw the sash against the frame, substantially as described.

45

4. In a window stay and fastener, a bracket fixed to the window sash, a link pivoted to said sash, a stay formed of two bars pivoted to said link and to said stay, a bracket fixed to the window frame, an end of each stay bar projecting beyond its point of pivoting in said link whereby when the stay is turned in said link, said ends will project beyond the face of the said link so that a space will be provided between such ends and the face of the said bracket on the window frame, a member pivoted to said bracket on the window frame, a portion of said member adapted to enter the space between the face of the said bracket on the frame and the said ends of the said stay bars and adapted to draw the sash inwardly, substantially as described.

50

5. In a window stay and fastener as claimed in claim 1, the inner edge of said projecting end of said stay bar being tapered whereby said tapered portion may draw the link inward and so draw the sash against the frame, a single bar pivoted in the ends of the said two stay bars, an end of said single bar projecting beyond the point of pivoting of said bar in said two stay bars, whereby when said bar is turned at its point of pivoting in said two stay bars, said end will project beyond the face of said two stay bars, a notch in the edge of the two stay bars engaging said bracket on the window frame, said notch being so positioned that a space will be provided between said ends and the face of said bracket, double tongues on said member pivoted to the bracket on the window frame to engage and bear on the two stay bars on each side of said bracket.

55

In testimony whereof, I have signed my name to this specification.

THOMAS PETER EUSTEDE
